UNITED STATES PATENT OFFICE.

CHARLES A. NAGEL, OF ALLEGHENY, PENNSYLVANIA, ASSIGNOR OF TWO-SIXTHS TO WILLIAM G. ANDERSON AND ONE-SIXTH TO MAX E. NAGEL, OF ALLEGHENY, PENNSYLVANIA.

ELECTRIC-ARC LAMP.

SPECIFICATION forming part of Letters Patent No. 783,974, dated February 28, 1905.

Application filed April 14, 1904. Serial No. 203,167.

To all whom it may concern:

Be it known that I, CHARLES A. NAGEL, a citizen of the United States, residing at Allegheny, in the county of Allegheny and State of Pennsylvania, have invented new and useful Improvements in Arc-Lamps, of which the following is a specification.

The object of my invention is to provide a new and improved arc-lamp; and to this end my invention consists of a new and improved arc-lamp, in the novel features of construction, and in the combination of parts, all as fully hereinafter described and claimed.

Among the principal objects of the present invention is to reduce the number of parts usually employed in lamps of this class. For example, I entirely dispense with the dash-pot and the usual magnets.

In the accompanying drawings, which illustrate an application of my invention, Figure 1 is an elevational view of a lamp constructed in accordance with my invention, and Fig. 2 a bottom plan of armature and choke-coil.

Referring to the drawings, the frame of the lamp comprises a slotted carbon-tube 1, a cross-piece 2, base 3, posts 4, extending upwardly from the base and carrying cross-piece 2, and a dependent hanger 5 for the lower carbon. This construction, except perhaps in details, is found in arc-lamps in general use and, it is believed, does not require a further description.

A choke-coil 6, comprising a core 7, of laminated soft iron, and coils 8, of insulated copper wire, taken in connection with armature 9, constitute characteristic and important features of the present invention. The core of the choke-coil in my invention is utilized as a magnet for actuating the armature.

The armature is connected to the carbon-clutch 10 by means of a jointed rod 11 and spring 12 and moves the upper carbon in the usual manner. The form of armature preferably employed is particularly shown by Fig. 2 and comprises in addition to the plate 9 a strip of soft metal 9^a. As illustrated, the armature is hinged to the core 7 of the choke-

coil by hinge 13; but instead of connecting the armature directly to the choke-coil it may be arranged in close proximity thereto. As shown, it is disposed so that one end of the plate 9 is nearer the choke-coil than the other and free end. The purpose of this is to have a portion of the armature so near the core of the choke-coil that it will at once respond to the magnetic attraction of said core. The upward pull is first exerted upon that portion nearest the choke-coil, and at the start the attraction is not as strong as it is after the remaining portion of the armature is brought nearer the choke-coil, when the armature has an accelerated movement. The armature is provided with a spring 14 to prevent vibrations of same against the choke-coil. The plane or planes in which the armature normally lies is or are inclined to the plane of the lower portion of the core of the choke-coil. Such a construction does away with the necessity of employing a dash-pot.

The core of the choke-coil, while shown U-shaped, may be of some other suitable form. In the drawings I have shown the core formed with inwardly-extending projections 15 and have arranged the armature in such a manner that the portion 9^a of armature will travel in the space between the two projections 15. The means for actuating the armature which in turn moves the carbon may be different from what is shown without departing from the scope of my invention, for among the features I desire to cover as my invention are means for operating an arc-lamp of this class without the use of dash-pots. I contemplate the employment of a magnet for actuating the armature, said armature employed for moving one of the carbons, and the said armature arranged in connection with the magnet in such a manner as to prevent flickering of arc whereby the use of a dash-pot is dispensed with.

For the purpose of limiting the downward movement of the armature I provide a stop 16.

What I claim is—

1. An arc-lamp having a choke-coil provided with inwardly-projecting portions, as

15, an armature connected with the choke-coil and actuated by the magnetism of the choke-coil provided with a strip of soft metal arranged to travel in the space between the projecting portions of the choke-coil, a carbon-clutch, means connecting the carbon-clutch and the armature, and a spring carried on the armature, substantially as set forth.

2. An arc-lamp having a choke-coil, an armature actuated by the choke-coil and connected thereto at one end, a spring on the free end of the armature adapted to make contact with the choke-coil when the armature is raised, a carbon-clutch, and means connecting the carbon-clutch and the armature, substantially as set forth.

3. In an arc-lamp, the combination, with the carbons, of a choke-coil, an armature actuated by the choke-coil, arranged so that a portion of the armature is normally in closer proximity to the choke-coil than its remaining portion whereby the armature is given a variable movement in its approach to the choke-coil, substantially as set forth. 20

In testimony whereof I have signed my name 25 to this specification in the presence of two subscribing witnesses.

CHARLES A. NAGEL.
